UNITED STATES PATENT OFFICE.

JOHN O. STINCHCOMB AND JOHN DANNER, OF CANTON, OHIO.

HAT AND CLOTHES HOOK.

SPECIFICATION forming part of Letters Patent No. 532,109, dated January 8, 1895.

Application filed November 20, 1893. Serial No. 491,398. (No model.)

To all whom it may concern:

Be it known that we, JOHN O. STINCHCOMB and JOHN DANNER, citizens of the United States, and residents of Canton, county of Stark, State of Ohio, have invented a new and useful Improvement in Hat and Clothes Hooks, of which the following is a full, clear, and exact description, reference being had to the accompanying drawings, making part of this specification.

Our invention relates to an improvement in hat and coat hooks, which consists of two hooks arranged one above the other, combined with a single base by which said hooks are secured; and particularly to that class of coat and hat hooks which are formed from a single piece of wire.

The invention has for its object, to provide the hook with a base, by which it is secured in position, and at the same time be braced from strain to which they are subjected when heavy articles of apparel are hung on them. Furthermore, to provide a device of this character which shall be simple of construction, durable in use and comparatively inexpensive of production.

With these objects in view, the invention consists of certain features of construction and combination of parts, which will be hereinafter described and claimed.

In the accompanying drawings, in which like letters of reference denote corresponding parts in the several views, Figure 1, is a view in perspective of our improved hat and coat hook, from right hand front. Fig. 2, is a similar view from rear left hand; Fig. 3, a side elevation of the base as secured to a support, and Fig. 4, a perspective of the base.

Referring to Fig. 2 of the drawings, the two hooks A and B, and the body C, are made from a single piece of wire, secured to a supporting base D. The upper hook A is formed substantially as shown, the parallel branches a d, extending horizontally out a distance, and at about right angles from the base designated as b at which point the branches are bent outwardly at a right angle to the branches a distance to a point designated as c, which points are connected by a bowed or arched portion d, vertically or thereabout over that portion of the wire between the points designated as b c. The object of this

structure is to form a large bearing or support for articles placed thereon. The second hook B, is formed of the branches e e, bent downwardly and forwardly and up and over as shown.

The hooks A, B, are connected by the upright portions C, C, which are secured to the base by lugs as hereinafter described.

The base D is formed substantially as shown in Fig. 4, having a vertical or body portion l, and a forwardly and upwardly projected brace m, side flanges n, having on their edges spurs o, and from the body portion, outwardly projected lugs as p. The web portion and the ends of the body are curved, as shown at q, said curvature serving to hold the wires against the flanged portion of the body. At a point about central to the body is provided an aperture r for a supporting screw.

The wire when formed as shown and hereinbefore described, is placed on the base D between the lugs p and the side flanges n, the branches resting on and supported by the outwardly and upwardly projected brace portion m, and are secured in position by the lugs p, bent down over and upon the wire as shown.

In use the hook is secured to a wall or other support by a screw, the spurs o drawn into the support as shown by the dotted line.

It will be seen that when in position the tendency to bend the hat hook A is entirely by the angular portion of the base, which serves two functions: namely, the bracing of the hook A and the means for connecting the ends of the wire, from which the hook is formed. The hook A is preferably extended laterally, and is of loop form, which will prevent the tearing of a coat when hung thereon, or the stretching of the same, which is objectionable in many hooks, having pointed ends.

From the foregoing description taken in connection with the accompanying drawings, the operation and advantages of the invention will be readily understood without requiring further explanation. The device is both simple and strong, and can be placed upon the market at such a price as to be within reach of all.

Having thus described our invention, we claim and desire to secure by Letters Patent—

In combination with a hat and coat hook

consisting in a single piece of wire formed into vertical branches C C parallel inclined branches *a a*, laterally extended branches *b c* terminating in an upward bowed portion *d*, and the lower ends of the uprights C C terminating in a hook B, a base plate having an angular extension *m* provided with bulged portions *q' q''* to take under and space and support the branches *a a*, marginal flanges *n n* and clamping lugs *p p* to embrace the vertical portions C C, penetrating lugs *o o* a screw

hole, and a screw by means of which the plate is secured to a support and prevented turning, substantially as herein described.

In testimony whereof we have hereunto set our hands this 15th day of November, A. D. 1893.

JOHN O. STINCHCOMB.
JOHN DANNER.
